(57) **CLAIM**

The ornamental design for a neck cooling device, as shown and described.

DESCRIPTION

FIG. 1 is a perspective view of the front, top and right side view of a neck cooling device according to a first embodiment showing my new design;

FIG. 2 is a front view thereof;

FIG. 3 is a rear view thereof;

FIG. 4 is a right side view thereof, a left side view being a mirror image;

FIG. 5 is a top view thereof;

FIG. 6 is a bottom view thereof;

FIG. 7 is a perspective view of the front, top and right side view of a neck cooling device according to a second embodiment showing my new design;

FIG. 8 is a front view thereof;

FIG. 9 is a rear view thereof;

FIG. 10 is a right side view thereof, a left side view being a mirror image;

FIG. 11 is a top view thereof; and,

FIG. 12 is a bottom view thereof.
